UNITED STATES PATENT OFFICE.

JOHN E. YOUNG, OF BRIDGEPORT, CONNECTICUT, ASSIGNOR OF ONE-THIRD
TO HENRY LETTERHAUS, OF SAME PLACE.

LOCK.

SPECIFICATION forming part of Letters Patent No. 325,305, dated September 1, 1885.

Application filed May 15, 1885. (Model.)

To all whom it may concern:

Be it known that I, JOHN E. YOUNG, a citizen of the United States, residing at Bridgeport, in the county of Fairfield and State of Connecticut, have invented certain new and useful Improvements in Locks; and I do hereby declare the following to be a full, clear, and exact description of the invention, such as will enable others skilled in the art to which it appertains to make and use the same.

My invention relates to those classes of locks which are especially designed to lock a movable to a stationary part, either by means of a hasp attached to one part and having a locking-stud at its end adapted to engage a hole in a lock-case attached to the other part or by means of a lock carried by a hasp attached to one part which is engaged by a locking-stud affixed to the other part, both styles being common—for example, both in trunk and car-door locks.

The object of my invention is to simplify and improve the construction of this class of locks, and to so arrange the mechanism within the case that the latter may be rotated, thus enabling me to cover and protect the key-hole, at the same time leaving the surface of the case perfectly smooth.

With these ends in view I have devised the simple and novel construction which I will now describe, referring by letters to the accompanying drawings, forming part of this specification.

I have illustrated my invention as applied to a lock of the class first described above—that is, in which the lock is permanently attached to one of the parts, and a locking-stud at the end of a hasp engages a hole in the lock-case.

Figure 1 is a plan view of the lock complete; Fig. 2, a central longitudinal section through the hasp and case, the locking mechanism being removed, and the locking-stud and the bolt which secures the case being in full lines; Fig. 3, an edge view of the locking mechanism on a greatly enlarged scale, as seen from the direction from which the key operates, a portion of the top of the case being in section. Figs. 4 and 5 are sections, looking down, on the line $x-x$ in Fig. 3, showing the parts, respectively, in the locked and unlocked positions,

the tumbler being replaced, however, in dotted lines to show its relation to the other parts, the position of the parts in Figs. 3, 4, and 5 being as if the lock as seen in Fig. 1 was turned over and the bottom plate of the case removed, the key being in elevation in Fig. 5 and in section on the line $y-y$ in Fig. 4. Fig. 6 is an edge view of the tumbler detached, the position being the same as in Fig. 3, and Fig. 7 is an end elevation showing the bits of the key.

Similar letters indicate like parts in all the figures.

A is the case of the lock, B the base-plate of the case, and C the hasp. The hasp is preferably jointed and provided with a slot, C', through which the attaching-bolt C² passes, thus permitting limited longitudinal movement of the hasp. The hasp is bent outward, then forward again to conform to the shape of the lock-case, and is provided at its locking end with a stud, D, which is adapted to enter a central hole, A', in the lock-case. The hasp is provided at any suitable place with a slot, C³, through which a turn-button, E, passes. This turn-button is firmly secured in a metal plate or in any suitable manner, and is provided with holes adapted to receive the ends of a wire, E, which are joined by a seal, E². The case of the lock is provided with bosses A², which receive the screws that hold the base-plate in position.

The center of the base-plate is provided with a circular depression, B', which sets down into the metal or wood, or both, to which the lock is attached. The purpose of this depression is to receive the head of the attaching-bolt B², so that the latter will be entirely out of the way of the locking mechanism. This bolt is the only means by which the lock is held in place, and its head is made round so as to permit the lock to be turned when it is desired to have the key-hole concealed by the hasp. The nut upon the bolt B² is of course tightened up sufficiently to prevent the lock from turning freely.

In order that the lock may be more easily turned by the hand, I have provided corrugations B³, which enable the hand to grasp it firmly.

Turning now to Figs. 3, 4, and 5, the posi-

tion of the parts is as if the lock in Fig. 1 was inverted and the base-plate removed, the view being into the case, which is shown as empty in Fig. 2.

5 F is a vibrating locking-bolt pivoted at one side of the case, and provided with a central opening, F', large enough to allow the enlarged head D' of the locking-stud to pass through it. The locking-bolt is provided upon 10 the edge opposite to the one acted upon by the key with a notch, F'', which is engaged when the parts are in the locked position by a stump, G', upon tumbler G. This tumbler swings from another pivot than the locking-bolt, but lies directly under it, or in the reversed position shown in Figs. 4 and 5 directly over it. At the center of this tumbler is an elliptical opening, G'', sufficiently large to receive the head of the locking-bolt in all 20 positions. Upon the edge of this tumbler, opposite to the key is a lip, G', which forms a bearing for spring, H, as will be again referred to.

K represents another tumbler pivoted near 25 the free end of the locking-bolt at some distance from the key-hole. This tumbler is provided with a stump, K', adapted to engage two notches in the edge of the locking-bolt opposite to its pivotal point, the action of this 30 stump when in engagement with notch F'' being to hold the locking-bolt in its locked position, and when in engagement with notch F' to hold it in its unlocked position. The locking-bolt is provided with a recess, F', upon its under side, which allows tumbler K to swing 35 under it.

L is a spring which acts upon tumbler K to force it forward against the locking-bolt.

M represents the key, which in the present 40 instance I have shown as provided with two bits, M' and M''.

As stated above, tumbler K swings under the locking-bolt. This is in order that said tumbler may swing into a position that will 45 enable one of the bits of the key to act directly upon the end of it.

It will of course be understood that the 50 shape of the bits of the key, the end of tumbler K, and the edge of the locking-bolt will be varied in different locks. In the present instance I have shown the tumbler as having a convex end, K'', to adapt it for engagement 55 with bit M'.

The action of the lock mechanism is as follows: It should be understood that, as seen in Figs. 4 and 5, the locking-stud enters from the back. It will be seen in Fig. 5 that openings A' in the case and F' in the locking-bolt register with each other, in which position the locking-stud will pass in or out freely. Turning 60 now to Fig. 4, the locked position of the bolt will be clearly seen. In locking, stud D passes through opening A' in the case and opening F' in the locking-bolt. The latter is 65 then moved to a position which places the opening through the bolt eccentric to the opening through the case, a portion of the

solid metal of the bolt passing under the head of the locking-stud, thus preventing the possibility of the latter being drawn out. When 70 the locking-bolt is in this position, it is guarded by two tumblers pivoted on different centers, which must be operated independently and successively before the locking-bolt can be moved.

75 When the parts are in the positions shown in Fig. 4, the operation of unlocking is as follows: The bits of the key move toward the right. Bit M' acts first on the convex edge of tumbler K, its action being that of a cam. As the bit is moved forward it passes over the convex end K'' and forces the tumbler backward—that is, toward the left—thus lifting stump K' out of notch F''. Bit M'' next acts 80 on tumbler G and raises stump G' out of notch F''. At this instant bit M', without releasing tumbler K, begins to act on the locking-bolt and raises it to the position shown in Fig. 5. Stump G' now rests upon the edge of the locking-bolt outside of notch F'', and stump K' 85 on the other tumbler drops into notch F', as shown.

90 In unlocking, tumbler K must be raised against the power of spring L, and tumbler G against the power of spring H, which acts on lip G''. It will be seen that there is no spring bearing directly on the bolt, and that when tumbler G is raised, the lip is carried away from the bolt, leaving the latter free from pressure, except from the key. In the action 95 of locking, however, spring H acts to force both tumbler G and the locking-bolt downward.

In unlocking, the key is turned toward the left, bit M' raises tumbler G slightly, then bit 100 M'' engages tumbler K, forcing it toward the left and lifting stump K' out of notch F''. By the time the locking-bolt is free, spring H has forced the lip against the bolt, stump G' having 105 passed into notch F''. The spring then continues to force both parts downward until the bolt is in the locked position, at which instant spring L forces stump K' into notch F' 110 in the locking-bolt.

I do not desire, of course, to limit myself to 115 the exact details of construction shown, as it is obvious that they may be varied within reasonable limits without departing from the spirit of my invention.

I claim—

120 1. The combination, with a lock-case having an opening and a locking-stud adapted to engage said opening, of a locking-bolt having an opening through which said stud passes, and notches upon two edges, and independently pivoted tumblers having stumps which engage said notches.

125 2. The lock-case having a central opening, and a locking-stud having an enlarged head, in combination with a pivoted locking-bolt 130 having an opening adapted to register with the one in the case and two notches in its outer edge, and a pivoted tumbler having a stump adapted to engage one of said notches

- when the openings register, and the other notch when said openings are eccentric and the solid metal of the bolt has passed under the head of the locking-stud.
- 5 3. The combination, with the locking-stud having an enlarged head, and the locking-bolt having an opening through which said stud passes, and a notch, F², of a tumbler, G, having a stump, G', opening G², and lip G³, and a spring acting on said lip.
- 10 4. The locking-stud and locking-bolt having a central opening and notches F², F³, and F⁴, in combination with tumbler G, having opening G² and stump G', and tumbler K, having stump K'.
- 15 5. The locking-stud and locking-bolt having central opening and notches F², F³, and F⁴, in combination with tumbler G, having a central opening, stump G', and lip G³, and tumbler K, having stump K' and convex end K³, as and for the purpose set forth.
- 20 6. The combination, with a locking-stud and a locking-bolt, of a case having a central opening to receive the locking-stud and upon its opposite side a depression and opening there-
- through, a bolt, B², passing through said opening and adapted to hold the lock in position, but which at the same time leaves it free to turn.
7. The combination, with the locking-stud 30 and case having a central opening and bosses A², and carrying the locking mechanism, of a base-plate secured to said bosses and having a central depression, B, an opening therethrough, and a retaining-bolt, B², whose head 35 rests in said depression.
8. The combination, with a hasp having a locking-stud at its end, of a lock-case having a central opening to receive the locking-stud and a key-hole in its outer side, and a central 40 retaining bolt whereby the case is held in place but is left free to be turned when it is desired to protect the key-hole by the hasp.
- In testimony whereof I affix my signature in presence of two witnesses.

JOHN E. YOUNG.
